(57) **CLAIM**

The ornamental design for an adjustable carrier strap, as shown and described.

DESCRIPTION

FIG. 1 is a lower right-front perspective view of an adjustable carrier strap;

FIG. 2 is a front view thereof;

FIG. 3 is a rear view thereof;

FIG. 4 is right side view thereof;

FIG. 5 is a top view thereof; and,

FIG. 6 is a bottom view thereof.

The broken line showing of an attached carried article, in FIG. 1, is for illustrative purposes only and forms no part of the claimed design.

The strap is shown broken away in the views to indicate indeterminate length.
